(57) CLAIM

The ornamental design for an ink cartridge, as shown and described.

DESCRIPTION

FIG. 1 is a perspective view of an ink cartridge;
FIG. 2 is a front view thereof;
FIG. 3 is a top view thereof;
FIG. 4 is a right side view thereof;
FIG. 5 is a left side view thereof;
FIG. 6 is a rear view thereof;
FIG. 7 is a bottom view thereof;
FIG. 8 is an enlarged partial cross-sectional view thereof taken along the line 8—8 of FIG. 4; and,
FIG. 9 is an enlarged partial section view thereof taken along the line 9—9 of FIG. 4.
The broken lines are for illustrative purposes only and form no part of the claimed design.
